[57] CLAIM

The ornamental design for a glider, as shown and described.

DESCRIPTION

FIG. 1 is a front perspective view of a glider showing my design;

FIG. 2 is a side elevational view, the opposite side being a mirror image thereof;

FIG. 3 is a front elevational view;

FIG. 4 is a top plan view;

FIG. 5 is a rear elevational view; and

FIG. 6 is a bottom plan view thereof.

FIG-1

FIG-2

FIG-3
